UNITED STATES PATENT OFFICE.

NANNIE D. HENLEY, OF RICHMOND, VIRGINIA.

COMBINED COAL-HOD AND ASH-SIFTER.

1,244,605.

Specification of Letters Patent.

Patented Oct. 30, 1917.

Application filed April 12, 1916. Serial No. 90,751.

To all whom it may concern:

Be it known that I, NANNIE D. HENLEY, a citizen of the United States, residing at Richmond, in the county of Henrico and State of Virginia, have invented certain new and useful Improvements in Combined Coal-Hods and Ash-Sifters, of which the following is a specification, reference being had to the accompanying drawings.

10 This invention is a combined coal hod and ash sifter.

The usual or customary mode of taking out ashes and sifting them is by using a solid bottom hod carrying the ashes therein to a separate receptacle for sifting. This involves two operations, one of putting the ashes into the hod and then dumping them into the ash sifter, which is not economical of either labor or time.

20 This invention aims to provide economical means for sifting ashes by saving at least one operation in the handling of the ashes.

Another object is to provide a device whereby the sifted portions, cinders, unburnt and partly burned coals are retained within a hod ready for use again.

A still further object is to provide a hod adapted to sift ashes deposited therein without the necessity of dumping into any receptacle for separate sifting. Another purpose of the invention is to provide a sifting hod with an ash receiving receptacle removably attached to the lower portion of the hod, said receptacle forming a convenient means for dumping into the final receiving ash can.

The invention broadly stated comprises a hod provided with a foraminous bottom adapted to be shaken or partly rotated in a horizontal plane, pins projecting inwardly and coöperating with the bottom, a handle, to shake or rotate the bottom and an ash receptacle adapted to coöperate with the lower portions of the hod, said receptacle being provided on one side near the upper or open edge with an inverted T-slot to receive the handle and the bottom of the re-

ceptacle being provided with a removable slide.

50 A practical form of the invention is illustrated in the accompanying drawings, in which—

Figure 1 is a perspective view of the hod and receptacle, showing the shaking handle; 55

Fig. 2 is a top plan view of the hod showing the foraminous bottom;

Fig. 3 is a sectional view of the hod showing the shaking bottom;

Fig. 4 is a sectional view of the receptacle 60 to show the slide.

In taking up ashes, it is usual in a household to employ a hod with a solid bottom but, in this invention, the usual or customary form of hod 5 may be employed 65 which has a foraminous bottom 6 which is adapted to be partly rotated or shaken within the hod 5. This foraminous bottom 6 may be retained in position by suitable pins 7. In order to more effectually break up 70 the contents of the hod, suitable projecting pins 8 may be employed. As the bottom 6 is preferably made circular in outline, it will be adapted to be rotated in a horizontal plane by means of a handle 9. This handle 75 9 projects outwardly in any convenient manner for shaking and is shown projecting through a slot 10 formed near the lower edge of the hod 5.

To coöperate with the hod, there is an ash 80 receptacle 11 provided which may be removably attached in any convenient or suitable manner to the hod 5 which, when combined or attached to the hod, forms a separable unit. Near the upper edge of the receptacle 85 there is formed an inverted T-slot 12, which has its longer axis in a horizontal plane. The handle 9 is adapted to be moved within the longer axis in order to shake or properly rotate the foraminous bottom 6. The receptacle 11 may be formed in any convenient manner or shape, though it is preferred to make it cylindrical and of sufficient height to contain the ashes which may be sifted into it from the hod. The bottom 13 of the 95 receptacle 11 is provided with a suitable

opening therein which may be closed by means of a slide 14 insertible from the exterior of the can. This slide 14 is provided with a handle 15 of any convenient form or 5 shape.

In the practical use of this device, in the removal of ashes from a household stove, the hod and the receptacle are connected together and the ashes upon being shaken 10 from the stove are placed within the hod. The hod is then taken to some convenient place, the handle 9 is actuated to rotate the foraminous bottom of the hod and the finer particles are caused to pass through the 15 foraminous openings and drop into the receptacle positioned beneath. After the contents of the hod have been thoroughly sifted and nothing but cinders or unburnt portions of coal remain therein, the hod is detached 20 from the receptacle. The receptacle is then positioned in the usual way upon an ordinary ash can such as is usually employed in households and the slide is withdrawn, thereby dropping the contents of the receptacle into the ash can. The hod and receptacle are again attached together and the 25 hod will then contain such material as may be used again for combustion purposes. Much labor is saved thereby as well as a 30 considerable saving in fuel.

Minor changes in form and details of construction may be resorted to as coming within the scope and spirit of the appended claims.

Copies of this patent may be obtained for five cents each, by addressing the "Commissioner of Patents, Washington, D. C."

What is claimed is:—

1. The combination with a hod having a movable ash sifting plate constituting the bottom thereof and provided with an operating handle, of an ash receptacle having means for co-operative engagement by said 40 handle whereby the hod and receptacle are detachably connected to each other.

2. The combination with a hod having a movable ash sifting plate constituting the bottom thereof and provided with an operating handle, of an ash receptacle provided with a slot to receive said handle, said handle constituting means for detachably connecting the hod and receptacle to each other. 45

3. The combination with a hod having a movable ash sifting plate constituting the bottom thereof and provided with an operating handle, of an ash receptacle having a horizontal slot in its vertical wall and a vertical slot communicating centrally with the 55 horizontal slot and opening upon the upper edge of said wall, said slots being adapted to receive the handle of the sifter plate, said handle being reciprocable in the horizontal slot and constituting means for detachably 60 connecting the hod and receptacle to each other.

In testimony whereof I hereunto affix my signature in the presence of two witnesses.

NANNIE D. HENLEY.
